PLASTER LATH BUNDLING MACHINE

Louis N. Sorensen and Joseph G. Fitzthum, Port Clinton, Ohio, assignors, by mesne assignments, to The Celotex Corporation, Chicago, Ill., a corporation of Delaware

Application May 16, 1938, Serial No. 208,326

4 Claims. (Cl. 216—22)

Our invention relates to improvements in plaster lath bundling machines and in particular to the means whereby the edge binding material is severed between the bundles as the said bundles advance continuously along the carrier chains.

Another object is to provide a means whereby removable spacers, mounted on the carrier chains at exact intervals, prevent crowding as the plaster lath moves continuously along on the said carrier chains.

These and other objects may be noted from the following specification and its accompanying illustrations, in which—

Fig. 1 is a top plan view of the bundling machine.

Fig. 2 is an enlarged fragmentary elevation of the knife and delivery end of the machine.

Fig. 3 is an end elevation of Fig. 2.

Fig. 4 is a view similar to Fig. 3, partly in section to show the knives in cutting position.

Fig. 5 is an enlarged fragmentary top plan view of one knife in sheathed position and operating means.

Fig. 6 is a similar view to Fig. 5 but showing the knife in cutting position.

Fig. 7 is a fragmentary side elevation of the knife operating mechanism with the knife carriage in the position shown in Fig. 6.

Fig. 8 is an elevation similar to Fig. 7 with the knife carriage in the position shown in Fig. 5.

Fig. 9 is a fragmentary end elevation of the knife mounting showing the ends of the plaster lath bundle and carrier chain.

Fig. 10 is a fragmentary top plan view of the carrier and spacer.

Fig. 11 is an end elevation of Fig. 10.

Fig. 12 is a side elevation of Fig. 10.

Again referring to the illustrations, the frame consists of a plurality of supporting members 10 to which are attached cross members 11 and base channel members 12. Shafts 13 and 13a, at opposite ends of the frame, support sprocket wheels 14 and 15 at the receiving and discharge ends respectively. Carrier chains 16 and 17 are mounted over said sprockets which are driven by means of a motor 18 through a variable speed drive 19, chain 20 and sprocket 21.

The carrier chain consists of a plurality of links 22 and link mounting lugs 23 having rollers 24 mounted between links 22 on pins 25. The link mounting lugs 23 have an angularly disposed center portion or plate 23a with an aperture 23b in the center thereof, said link mounting lugs being mounted on pins 25 on the outside of the links 22, positioned in such manner as to form

a link chain as illustrated in Figs. 10, 11 and 12, with the plate portion 23a uppermost; secured to certain parts of the inwardly projecting plates 23a by bolts 26 are spacer plates 27 having angularly disposed center portions or separators 27a, and these spacer plates are secured to the chain 23 at spaced intervals.

The separators 27a serve to divide the bundles of plaster board or lath and convey them forward over the carrier chains from the loading end to the discharge end.

Gummed tape rolls 29 and 29a are mounted on pins 30 and 30a on opposite sides of the frame outside of the carrier chains 16 and 17, and said gummed tape passes between wetting rollers 31 and 32 around guide rollers 33 and are folded over the bundles of lath 34 by folders 35, the lath being properly lined by the guide roller 36 and plate 37.

The gummed tape is held in contact with both edges of the bundle of lath 34 by rollers 39 and 39a until the glue has set, rollers 40 and 40a traveling on the folded over edges at the top and bottom respectively of the lath, to seal the bundles together.

The bundles travel forward until they reach the traveling knives 41 which cut the continuous strip of gummed tape at the separating plate 27a.

The knife assembly consists of guide shafts 42 mounted within bosses 43 on the frame structure, a sleeve 44 superimposed over the shaft 42 which has a plate 45 mounted thereon and a tie bar 46 mounted between apertures 47 in the knife guides 48.

The knives 41 have arms 49 secured thereto at their outer edges, said arms having roller shafts 50 mounted through the curled outer ends thereof, the roller shafts terminating in rollers 51 and 51a at their lower ends. The inner edges 41a of the knives 41 are serrated to facilitate the cutting operation.

Forward on the plates 45 are mounted bearing blocks 52 having bearings 53 at the rear ends and adjacent the edges thereof. Rotatable shafts 54 are mounted therein. Driving rods 55 are secured at one end through the rotatable shafts 54 by nuts 56 screwed over the projecting threaded ends of said rods, the opposite threaded ends of the driving rods 55 being screwed within bearing brackets 57, said brackets have apertures 58 therein transversely of the threaded end and through which are mounted pivot pins 59, said pivot pins being the means whereby the driving rods 55 are secured to link chains 60 which are mounted on sprockets 61 and 62 and 63.

which have a travel length that is the same distance as that between the spaced separating plates 27a and are synchronized with the carrier chains 16 and 17 so that the knife assembly makes one complete trip, forward and back for each bundle of lath.

Angular or offset stationary tracks 63 on opposed sides of the frame and adjacent the respective knife assembly are mounted on platforms 64 as illustrated specifically in Figs. 5 and 10 6. Pivoting track dividers or switches 65 are spaced approximately in the center of the platforms 64; levers 66 on the underside of the platforms 64 are secured to the pivot 67 and levers 15 68 are pivotally attached to the platforms by pins 69.

In action, Fig. 5 illustrates the return of the knife 41 from the cutting stroke as shown in Fig. 8, as the knife travels back the carriage at indicated point 70 contacts the lever 66 and causes said lever to move toward the outer side of the bundler turning the track divider or switch 65 to the position shown in Fig. 6. The knife 41 then starts forward on its cutting stroke, the roller 51 striking the track divider causes said knife to move inwardly severing the bundling tape between the bundles 34.

As the knife moves forward the roller 51 pushes against the track divider 65 causing it again to assume the position shown in Fig. 5. The lever 66 contacts the lever 68, thus when the point 71 of the knife assembly strikes the lever 68 the track divider 65 again assumes the position shown in Fig. 6. As the knife 41 returns the track divider 65 keeps the knife from moving inwardly thus preventing damaging a bundle or jamming the knife. The forward half of the track divider 65 and the lever 68 are not necessary to the proper functioning of the knife assembly but are installed as a safety measure to prevent jamming of the knife by inadvertent bumping of the knife roller 51.

The line of travel of the roller 51 and the knife 41 are indicated on Figs. 5 and 6 by arrows.

Figs. 7 and 8 show a slightly different knife assembly mounting, a shorter plate 45a is used and a pair of shorter sleeves 44a and 44b in place of the long plate 45 and sleeve 44 shown in Figs. 5 and 6.

In operation the bundles of lath travel along with the conveyer chains, to the left in Fig. 1, and as they travel the tape or binding material 29, 29a, is applied to the side edges of the bundles, the bundles being spaced and advanced by the plates 27a between the bundles. As the bundles reach the knife stations the knives are projected inwardly between the bundles by the cam action of the switch plates 65, as the knife carrier 45 advances, said advance being at the same speed and direction as the travel of the bundles, whereby the knife completes its stroke without stopping the travel of the bundles, and after the binding tape is cut the cam track 63 acting on the

roller 51, withdraws or retracts the knife which is then carried back to original position by the action of the chain belt 60 and connecting rod 55, for the next operation, the switch 65 being thrown by the action of the lever 66 to permit the roller 51 to pass back without advancing the knife.

It will be seen that by means of the spacers 27a the bundles are held in exact arrangement or series with spaces between into which the knives may enter, and that the knives are advanced at 10 opposite sides and also travel along with the bundles to sever the tape between the bundles without stopping the travel thereof.

Various changes in the structure are possible within the scope of the invention and the following claims.

We claim:

1. In a machine for binding lath bundles, the combination with reciprocating knives movable between the bundles to sever the binding, of 20 means to operate each knife, said means including a carrier reciprocating in a line parallel to the line of movement of the bundles, and a cam track operating on the knife to advance and retract the same, said track including a switch 25 operated by the carrier to permit the backward movement thereof without advancing the knife.

2. The combination stated in claim 1, the means to operate each knife comprising a reciprocating knife carrier traveling beside the 30 bundles and a cam track operating on the knife and including a pivoted cam switch acting to advance and retract the knife during the advance of the carrier, and a lever operated by the carrier and connected to the switch to throw the same 35 at the end of said advance of the carrier and to permit return of the carrier without advancing the knife.

3. The combination stated in claim 1, the means to operate each knife including a reciprocating carrier working beside the bundles and having a guide for the knife, a roller attached to the outer end of the knife, and a cam track for the roller, said track having a pivoted switch 40 engaging the roller and formed to advance the knife during movement of the carrier in one direction, and means operated by the carrier to throw the switch and permit bypass of the roller without advancing the knife on the return movement of the carrier.

4. The combination stated in claim 1, the means to operate each knife comprising a guide rod parallel to the line of travel of the bundles, a reciprocating carrier on said rod, having a guide for the knife, a cam track beside the carrier, and operative means between the cam track and the carrier constructed to advance the knife inwardly when the carrier is moved in one direction and to hold the knife retracted when the carrier is moved in the opposite direction.

LOUIS N. SORENSEN.
JOSEPH G. FITZTHUM.
